PROPELLER ARRANGEMENT

Application filed July 15, 1931, Serial No. 550,977, and in Germany July 26, 1930.

The hitherto known air and water propeller is open to the objection that it only acts rationally, when the resistance opposing the forward movement of the vehicle is very slight in proportion to the available power, so that the vehicle thus can easily follow the rapidly progressing propeller, otherwise, a large portion of the motive power is lost by slipping. If, for example, an aeroplane having a total weight which is of 5 kilograms per H.P. assumes a vertical upward position, it slips backwards and if a racing boat is on a shallow from which a boy could free it by means of a rope or a pole, it is often not capable of getting free with its propeller and its many H.P. motor. Consequently it was also impossible for screw steamers to always travel economically with the continually varying travelling resistance, to stop quickly enough in the event of danger and to immediately free themselves with their own power when they have run on to a shallow. Consequently aeroplanes can, up to the present, only start with difficulty and remain steady in the air in the case of gusts of wind. And it was for this reason hitherto not possible to construct the only ideal air transporting means, which rises directly, without requiring too voluminous planes, remains in the air and propels economically. Likewise it has not been possible to produce a land propelled vehicle of light weight so necessary as to form a perfect substitute for the horse, especially in agriculture, and which is no longer dependent upon the adhesion on the ground, which is often too soft and often too slippery, and which only with difficulty obtains a sufficient support in the air.

This objection is entirely overcome according to the invention in that the propeller for the vehicle, which requires provisionally or continually a strong impetus and at the same time must travel even a short distance quietly, is so constructed and so fitted on the vehicle and, whilst producing and imparting driv-

ing force, is so guided that it always grips the medium sufficiently strongly in order to be carried thereby and obtain the necessary impulse without slipping, even if the travelling resistance is very great as compared with the motive force. The vehicle will thus be driven forward slowly even with a travelling resistance of one hundred or more kilograms per H.P., and correspondingly quicker as the travelling resistance reduces.

An embodiment of the invention is illustrated by way of example in the accompanying drawing in which:

Fig. I is a vertical longitudinal section of the arrangement.

Fig. II is a front elevation of such an arrangement with rigid blades.

Fig. III shows an arrangement with propellers loosely mounted on the axles and arranged for forward and reverse drive.

Fig. IV is a diagram showing the manner of operation of the new propeller with rigid blades.

Fig. V is a similar view showing the operation of a propeller with hollow reversible blades.

Figs. VI and VIII are longitudinal sections of Fig. V.

Fig. VII is a front elevation of Fig. V.

The drawing shows the vehicle frame 1 with the driving shaft 2 rotated by the blades 3, either by means of its hub 4, which is rigidly mounted on the driving shaft 2 (as in Figs. I and II) and a blade-shaped blade root slightly flexible in axial direction; or by means of a catch arm 5 rigidly connected to the driving shaft 2 and which rotates by means of its contact cheeks loosely mounted on the driving shaft and inclined or provided with balls with axial play, as illustrated in Fig. III; or by a blade-shaped transverse axle 6 rigidly connected to the driving shaft 2 in the inside of the blades or their edges, but hingedly connected to the blades. On the individual blades a steel cam 7 is pro-

vided by means of which the impetus of the blades is transmitted to the vehicle. An impetus receiver 8 is arranged on the vehicle for taking this impetus, the receiver 8 consisting of a ring with a very flat projection or of slightly conical rollers arranged in a circle. The pressure ring and thrust bearing are no longer necessary, and the shiftable bearing 11 now serves for adjusting the rotary blades (Figs. VI-VIII) for forward and reverse impulse.

In the known propeller arrangement the blades cannot actually screw forward in a helical line immediately after they are started up, but are compelled to rotate in a circle until they have gained sufficient speed and develop thrust force to effectively propel the vehicle. They therefore produce right from the outset of the rotation a rearwardly directed flow of the medium, which is desirable for a fan but is very detrimental for a propeller, as this obtains no solid support on the rearwardly escaping medium and thus effects no strong thrust and can overcome no strong resistance. Moreover this unnecessary and detrimental flinging back of the medium remains more or less, even during effective propelling of the vehicle, as this can never follow the propeller with the axial speed corresponding to its screw operation.

In the new arrangement however, as can be seen from the diagram illustrated in Fig. IV, the working surface 3 screws itself slightly forward in the direction of travel immediately after it is set in operation, leaving the vehicle behind, that is without contacting with its thrust receiver 8, and travels in its helical line corresponding to its pitch, out of the position A into the position B as it does not as yet need to drive the vehicle, that is, its cam surface 7 does not contact with the thrust receiver 8. This mutual contacting occurs only during the further rotation in the position B in which the cam surface 7 of the blade strikes against the thrust receiver 8 and is first compelled by this (or more correctly by the traveling resistance of the vehicle rigidly connected to the receiver) to pass slightly forward out of its free helical slightly forwardly directed movement (shown at top of illustration) to the axially slightly rearwardly displaced position (shown at bottom of illustration). The blades at the contact point are of double wedge-shaped cross section, with the taper of the working surface 3 longer than that of the cam-surface 7.

During this short travel, the actual working operation, the working surface 3 presses and suddenly the medium, which has remained substantially constant up to this minute, out of its position of rest and forces it very quickly axially towards the rear, thereby exerting a flat blow with its entire wide side (shown in the bottom of drawing).

As however air and water, as is known, offer at first but not for long an extremely great resistance to the rapid displacement out of the position of rest, which resistance is a hundred times greater than in the eddy of the known propeller, the thrust receiver 8 will be pushed strongly forward if the blade strikes sufficiently rapidly and not too far towards the rear and the resistance is not too great, that it does not exceed about 200 kilograms per H.P. This forward movement is due to the strong initial resistance of the medium against its sudden displacement towards the rear, so that the vehicle is strongly pushed forward in its direction of travel.

As soon as the medium is pressed so strongly towards the rear or the vehicle is pushed so far in forward direction that the blade reaches the position C, this ceases to push the vehicle as it has lost contact with the air. It can consequently continue to move on freely and unimpeded in its helical line towards the point D and the operation thus repeats itself.

During the travel of the blade from B to C, the medium, owing to the speed and short duration with which it is beaten by the entire wide side of the blade, has not time to properly come out of its position of rest and to escape towards the rear. Consequently it can no longer form and continually supplement a rearwardly directed strong current which would hinder to a maximum extent the further strong gripping of the blades. The air on the pressure side of the blade is slightly compressed (see bottom of illustration) and working surface 3 is forced towards the rear the air being slightly rarefied on the suction side so that the working surface sucked towards the rear, but in reality only a fraction of a millimetre and only during a short time which is insufficient for the complete starting up. Then in the next moment the blade during its long path from C to D the working surface screws forward again alone, without the vehicle, and cuts the medium exactly in its helical line as far as it is not prevented by the mass proper from being axially accelerated to a minimum relative to the vehicle, that is without displacement more towards the rear than towards the front, so that with very slight weight it only produces very slight flowing and during the next sudden attacking of the medium can form a supporting point almost exactly as strong as the first time, and the rotary force of the engine is always almost completely converted into effective impulsion of the vehicle. Moreover owing to this flow being lacking, the blades according to the new arrangement, can rotate much more quickly than heretofore without losing in efficiency. Consequently the new propeller may also be enclosed in a narrow space, have a much larger number of blades and a much

smaller diameter, and be driven directly from the high speed engine without reduction gear.

The manner of operation in the construction according to Figs. VI-VIII is in principle the same. In this instance, according to the diagram shown in Fig. V, the working surface 3 of the blade suspended on the transverse axle 6 and pushed on in front of same 10 when travelling on, is pushed by the medium out of the inoperative position A, because it does not require to push on the vehicle, and comes into the position B, with its front edge somewhat axially in advance (see upper portion of illustration). In this position it contacts with the roller 10, which does not arrest it in its rotation, but forces it to suddenly yield slightly axially in the opposite direction to that of travel, and to suddenly effect 20 a rapid and short flat blow against the stagnant medium until, owing to the great resistance of same against rapid displacement, it has wedged the roller and with same the impulse receiver 8 and the entire vehicle sufficiently to pass, the roller and thus come in 25 the position C, where the working period is terminated. It then proceeds to again form a solid cushion and to effect a fresh forward push of the vehicle supported thereon, owing 30 to its free forward screwing into the position D.

The vehicle moves easier and further forward under the individual impulses and retains the acceleration received for a longer 35 period the less the travelling resistance is, so that the maximum speed of travel corresponding to the actually existing conditions of power and resistance is automatically obtained without a change gear, such as is necessary in the known motor cars. In order 40 that the vehicle does not receive excessive impulses from the entire propeller and must continue to travel for a longer period exclusively by its inertia moment, the number 45 pairs of blades (here four) and that of the contacts 9, 10 are selected so that they come into contact at different times and during the working pause of one pair of blades the strong impulses of the remaining pairs occur 50 successively and thus effect a practically uninterrupted and vibration-free strong thrust.

In order to allow the vehicle to run backwards, the driving shaft 2 is, according to Figs. III and VIII, merely allowed to circulate in the opposite direction. The blades 55 then press with their rearwardly directed cam surfaces 7 onto forwardly directed projections 9 of the pressure receiver 8 in an analogous manner to that above described and illustrated in Fig. IV for the forward repulsion. In the arrangement according to Figs. VI-VII or V, the reversing gear bearing 11 and therefore also the transverse axle 6 is merely pushed slightly towards the front 60 (top of illustration). Consequently the

working surfaces are situated with their front edge directed towards the rear and exert the above described operation as a strong rearward pull, as shown diagrammatically in the second portion of Fig. V, where the blade 70 screws freely forward out of the position A' into the position B' and, between its positions B' and C', is forced forwards by the rollers 10' and thus exerts the thrust towards the rear indicated by the vertical arrow. 75

An invention apparently similar, of the same inventor, is known, but has not attained its aim, because in inverse manner, instead of preventing the slipping, it is based on the periodical storing of the ordinary thrust force of the propeller, in the form of a mass acceleration, and in the intermittent imparting of this stored force to the vehicle, whereas in reality it is exactly the opposite to that which is here the case, the working supporting surface during its axial oscillations must be free from all unnecessary mass and consequently the operation is also not destroyed by the elasticity, the axial forcing back of the blades against the medium and also the imparting of the blade thrust to the vehicle must not occur through the propeller axle or even through a ring arranged on a disc mounted on the axle, but only by direct contact between the vehicle body and the thrust centre of the blade surfaces, as is here attained. 85

In order to render possible this strong striking back and the rapid screwing forward of the working surface of the blades and to render same as far as possible independent of the superfluous mass, especially also that of the hub or at least of the axle 2, the necessary means are here employed as shown in Figs. I, III, VI and VIII and set forth in claims 2 100 to 7. Moreover the blades may be made of lighter weight with a much more favorable shape, as regards to efficiency and safety against fracture, than in the known system, as they are actually supported at their most delicate points slightly out of their centre by the thrust receiver as soon as they develop thrust force. 105

Further, in order to prevent the good efficiency from suffering through the sliding friction on inclined pressure surfaces, rollers 10 are employed in practice instead of the pressure surfaces 9 on the impulse receiver 8, shown for the sake of clearness. 110

I claim:

1. A propeller arrangement for propelled vehicles with short striking blades, comprising in combination a driving shaft, blades mounted on and adapted to rotate with said shaft axially shiftable during the work, actual working surfaces of said blades arranged with axial play, means for causing axial pushing back of each of said working surfaces individually at its centre of pressure for effecting a flat blow and imparting a pro- 125

- steller thrust produced, a thrust imparting element for each of said blades, and a thrust receiving element for each of said blades, said means becoming operative between said 5 thrust imparting element and said thrust receiving element.
2. An arrangement as specified in claim 1, comprising in combination with the blades and the axially fixed driving shaft, a thin 10 plate resilient in axial direction and rigid in turning direction connecting said blades adapted to allow the free axial screwing forward and striking back of said blades independently of said shaft.
- 15 3. An arrangement as specified in claim 1, comprising in combination with the blades and the axially non-shiftable driving shaft, an arm rigidly mounted vertically on said shaft adapted to allow the free axial play of said blades on said shaft and to pull said blades towards their front edges and to push said blades towards their rear edges during its rotation.
- 20 4. An arrangement as specified in claim 1, comprising in combination with the blades and the driving shaft, a hub carrying said blades loosely and shiftably mounted on said shaft, catch arms rigidly connected to said shaft adapted to impart the rotary power to said blades, contacting cheeks on said catch arms inclined to the axis of said shaft, and contacting cheeks on said blades also extending at an incline to the axis adapted to move slightly away from the contacting cheeks on 25 said catch arms during the axial shifting back of said blades to allow the free axial play of said blades.
- 30 5. An arrangement as specified in claim 1, comprising in combination with the blades and the driving shaft, a hub carrying said blades, loosely and shiftably mounted on said shaft, catch arms rigidly connected to said shaft adapted to impart the rotary power to said blades, contacting cheeks on said catch arms, inclined to the axis of said shaft, contacting cheeks on said blades also extending at an incline to the axis adapted to move slightly away from the contacting cheeks on 35 said catch arms during the axial shifting back of said blades, and guide rollers between said cheeks adapted to allow the free axial play of said blades.
- 40 6. An arrangement as specified in claim 1, comprising in combination with the blades and the driving shaft, a hub carrying said blades, loosely and shiftably mounted on said shaft, catch arms rigidly connected to said shaft adapted to impart the rotary power to said blades, contacting cheeks on said catch arms inclined to the axis of said shaft, contacting cheeks on said blades also extending at an incline to the axis adapted to move slightly away from the contacting cheeks on 45 said catch arms during the axial shifting back of said blades, and an elongated ele- 50 ment slightly axially bendable backwards and forwards adapted to shift apart said cheeks to allow the free axial play of said blades.
- 55 7. An arrangement as specified in claim 1, comprising in combination with the axially non-shiftable driving shaft and the blades, elements adapted to rotate said blades to enable the free play of said blades independently of said shaft, said elements causing an outflow at their edge opposite to the desired direction of rotation.
- 60 8. An arrangement as specified in claim 1, comprising in combination with the axially non-shiftable driving shaft and the blades, elements adapted to rotate said blades to enable the free play of said blades independently of said shaft, said elements causing an intermittent reaction at their edge opposite to the desired direction of rotation.
- 65 9. An arrangement as specified in claim 1, comprising in combination with the blades, small inclined projections in the pressure centre of said blades adapted to effect the alternating short freeing of said blades from the thrust of the vehicle and the still shorter 70 reloading of same and to cause a strong forward drive of the vehicle, a thrust receiver, and rollers on said thrust receiver adapted to come into contact with said projections during the free forward screwing of said blades.
- 75 10. An arrangement as specified in claim 1, comprising in combination with the blades, small inclined cams in the pressure centre of said blades adapted to effect the alternating short freeing of said blades from the thrust of the vehicle and the still shorter 80 reloading of same and to cause a strong forward drive of the vehicle, a thrust receiver, and rollers on said thrust receiver adapted to come into contact with said cams during the free forward screwing of said blades.
- 85 11. An arrangement as specified in claim 1, comprising in combination with the blades, small inclined projections in the pressure centre of said blades adapted to effect the alternating short freeing of said blades from the thrust of the vehicle and the still shorter 90 reloading of same and to cause a strong forward drive of the vehicle, and rollers on the vehicle frame adapted to come into contact with said projections during the free forward screwing of said blades.
- 95 12. An arrangement as specified in claim 1, in which the rapid pressing back of the freely screwing forward blades on encountering the thrust receiving element is effected by a pressure liquid between the thrust imparting element and the thrust receiving element.
- 100 13. An arrangement as specified in claim 1, in which the rapid pressing back of the freely screwing forward blades on encountering the thrust receiving element is effected by the reaction of a body between the thrust imparting element and the thrust receiving element.
- 105 14. An arrangement as specified in claim 1,

comprising in combination with the blades adapted to swing axially independently the ones to the others and the thrust receiving element, a plurality of cams on said blades,
5 a plurality of projections on said thrust receiving element adapted to produce an uninterrupted and vibrationless thrust on the vehicle.

10 In testimony whereof I affix my signature.
